Primary Examiner — Darlington Ly(74) *Attorney, Agent, or Firm* — Ian K. Samways(57) **CLAIM**

The ornamental design for a cutting head for rotary drill, as shown and described.

DESCRIPTION

FIG. 1 is a top, front and left side isometric view of the cutting head for rotary drill showing my new design;
 FIG. 2 is top, front and right side isometric view thereof;
 FIG. 3 is a bottom and right side isometric view thereof;
 FIG. 4 is a right side elevation view thereof;
 FIG. 5 is a left side elevation view thereof;
 FIG. 6 is a front side elevation view thereof;
 FIG. 7 is a rear elevation view thereof;
 FIG. 8 is a top plan view thereof; and,
 FIG. 9 is a bottom plan view of thereof.
